PORTABLE CONVEYER LOADER

Filed Nov. 14, 1928

Fig. 1.

UNITED STATES PATENT OFFICE

JOHN P. POLSTER, OF ALTON, ILLINOIS, ASSIGNOR TO DUNCAN FOUNDRY AND MACHINE WORKS, INC., OF ALTON, ILLINOIS, A CORPORATION OF ILLINOIS

PORTABLE CONVEYER LOADER

Application filed November 14, 1928. Serial No. 319,404.

This invention relates to certain new and useful improvements in portable conveyer loaders for mine cars and other purposes, the peculiarities of which will be hereinafter 5 fully described and claimed.

The main objects of my invention are to provide a conveyer loader with an auxiliary feeder conveyer adapted to be swung in a wide arc on either side of the main conveyer and deliver thereinto in any adjusted position, and thus allow of collecting coal from a fan-shaped area or around a post or corner, without necessarily changing the point of delivery; secondly, to support said 10 feeder pivotally from the main conveyer; thirdly, to operate said feeder from the drive of the main conveyer whatever the adjusted position of said feeder; and fourthly, to provide other features hereafter 15 described and claimed.

In the accompanying drawing in which like reference numerals indicate corresponding parts—

Fig. 1 represents a side elevation of a 20 machine exemplifying my invention;

Fig. 2, an end view of the main frame, section of the feeder support and longitudinal shaft on the line 2—2 of Fig. 1;

Fig. 3, a sectional elevation on the line 25 3—3 of Fig. 1;

Fig. 4, a plan view of the feeder support on the horizontal plane 4—4 of Fig. 1;

Fig. 5, a plan view of the loader with feeder swung to one side; and

Fig. 6, a detail of the conveyer chain enlarged.

Referring to the drawing, the numeral 5 designates carrying wheels, flanged for track rails or otherwise, and supporting a 30 rectangular main frame.

This frame preferably consists of posts 7 and 8, horizontal side bars 9, 10 and 11 with braces, and cross bars for a motor 12 adapted for electric connection and operatively connected by flexible coupling and worm gearing or otherwise, to a chain drive,—the main shaft 13 of which is preferably mounted in boxes 14 on the side bars 11. A double line of conveyer chain 15 and cross bars 16, are 35 carried over sprockets on end shafts 17

and 18 mounted at the ends of a conveyer trough 19 that is supported on said posts 7 and 8 of the rectangular frame. These cross bars are preferably T-section, with ends bent and provided with holes corresponding to the chain pitch for special pivot pins 20 that are longer than the standard pins 21 and drilled for cotters, so as to pass through the bent ends of said bars, and be secured. Two of these special pins 20 at each end of said bars connect with the adjacent chain link and avoid the usual special link attachment.

Each chain is engaged by a sprocket wheel 22 mounted on each end of said main shaft 13, and is provided with a guide sprocket 24, and tightener sprocket 23 mounted on a spring-controlled pivoted arm 25, as shown in Fig. 1.

On the main shaft 13 is also mounted a 70 driving sprocket 26, connected by a chain 27 with a sprocket 28 on a horizontal cross shaft 29 mounted in boxes 30 supported by said posts 7. A casing 31 supported by said boxes or otherwise, encloses bevel gears on 75 said shaft 29 and on a vertical shaft 32 that extends into an upper casing 33, which has a swing joint connection at 34 with the lower casing. A pivot pin bolt 35 in the axis A of the vertical shaft, connects a flat bar tongue 36 with the flange of an angle cross bar 37 supported by said posts 7. The upper casing is secured to said tongue and swings with it.

A horizontal longitudinal shaft 38 has 80 one end mounted in the upper casing, and is driven by the vertical shaft through bevel gears in the upper casing which are mounted on the vertical and longitudinal shafts respectively. The other end of the 85 shaft 38 is mounted in a casing 39 supported by leg boxes 40 from a platform 41 fastened on the wide end of a supporting frame formed by bars 42, converging toward and secured to said tongue 36, and having 90 lower converging braces 43 and vertical struts 44. A flat bar tongue 45 secured to the adjacent ends of the said braces, is pivoted in the axis A of the vertical shaft 32 by a bolt 46, to the flange of a lower angle 95 100

cross bar 47 or otherwise, at the bottom of the posts 7. A pivotal truss frame of narrow width and considerable depth at the tongue end, and diverging horizontally and converging vertically towards the platform 41, is thus formed.

A horizontal cross shaft 48 is mounted in said leg boxes and casing 39, and has a bevel gear driven by one on the front end of the longitudinal shaft 38. Sprocket wheels 49 are mounted on the ends of shaft 48.

Secured to said supporting frame at the ends of the platform 41 are side plates 50, pivotally connected by bolts 51—or otherwise—in the axis of the shaft 48 to upper plates 52 depending from the sides of an auxiliary conveyer trough 53, the front end of which is on or near the ground and the rear end positioned over the front receiving end of the main conveyer as shown in Figs. 1 and 5, to discharge thereinto. This feeder trough has a chain conveyer similar to that of the main conveyer, with chains passing over sprockets on shafts 54 and 55 at its ends, and engaging said sprocket wheels 49. A tightener sprocket 56 in a spring-controlled frame 57, is provided for each chain.

The receiving front end of this feeder trough is preferably provided with a deeper side angle 58 to support a wood backing 59 below the plate bottom of the trough, and serve as a shock absorber to prevent the plate bottom being bent into hollows by the heavy pieces of coal or rock dumped into it. This wood backing also serves to deaden and reduce the spring tendency of the plate bottom, as well as to avoid the weight of the feeder if it were provided with a plate bottom thick enough to prevent indenting under the blows of the material dumped upon it.

The feeder and main conveyer are thus adapted to be driven from one motor, and the feeder to be operated in any position to which it may be swung about the vertical axis A, as indicated in Fig. 5, and discharge into the main conveyer, which latter will continue to discharge at the same point as before unless it is moved on the track. The feeder is so balanced on its pivotal connection with the truss frame, that its front end is easily raised from the ground to swing it horizontally to any desired point of a wide semicircle where coal is to be dumped into the feeder.

The side bar 11 of the main frame is bolted or otherwise secured to the posts 7 and 8, so as to be readily removed and allow access to the motor and other drive mechanism for removal and replacement.

I claim:

1. A conveyer loader comprising a main conveyer, a feeder conveyer, a supporting

frame for the feeder conveyer having upper and lower pivot tongues in a vertical axis adapted to swing about said axis, a gear casing carried by the upper tongue so as to form a swing casing, a fixed gear casing mounted on said main conveyer in said vertical axis below the swing casing, a vertical shaft between said casings and in said vertical axis, operative connections between said vertical shaft and the feeder conveyer, a horizontal shaft mounted on the main conveyer and passing through the fixed casing and operatively connected to the vertical shaft, and driving means for the main conveyer and operatively connected to said horizontal shaft.

2. A conveyer loader comprising a main conveyer, a fixed lower casing on the front of the said main conveyer, an upper casing having a swing joint connection upon the lower casing, a truss frame pivoted in the rear above and below said casings in their vertical axis and secured to the upper casing, a feeder conveyer pivoted by the middle to the wide front end of said frame on a horizontal axis, separate drag mechanisms for the main and feeder conveyers, operative connections located in the vertical axis of said casings and the horizontal axis of said pivotal support of the feeder, and driving mechanism for the main drag mechanism, substantially as described.

3. A conveyer loader comprising a main conveyer and its driving mechanism, a feeder conveyer and its driven mechanism, upper and lower supporting side plates located midway below said feeder and pivoted together in pairs on a horizontal axis, a supporting frame comprising bars and braces secured at their front ends to the lower pair of said side plates and converging horizontally at the rear to upper and lower tongues in a vertical axis through pivot connections with said main conveyer, cross bars at the front of the main conveyer and pivotally connected to said tongues in said vertical axis, and operative connections between said driving and driven mechanisms, substantially as described.

4. In a conveyer loader comprising a main conveyer, and a feeder conveyer having depending side plates in pairs pivoted together, the herein described pivotal truss frame consisting of bars and braces connected in a horizontal axis at the front to said side plates and converging horizontally and diverging vertically rearward to tongues spaced apart on a vertical axis and having vertical struts connecting said tongues, and matching supports on the main conveyer for the pivot connections of said tongues respectively, substantially as described.

5. A conveyer loader comprising a main conveyer and its driving mechanism, a feed-

er conveyer and its driven mechanism, a pivotal truss frame pivotally connected to both said conveyers and having a wide front end platform, boxes thereon, a horizontal cross shaft mounted in said boxes and operatively connected to said feeder mechanism, and a longitudinal shaft having its ends operatively connected to said cross shaft and the driving mechanism of the main conveyer
10 respectively, substantially as described.

In testimony whereof I have affixed my signature.

JOHN P. POLSTER.
